UNITED STATES PATENT OFFICE.

ERNEST L. TEICH, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR CLOSER.

Application filed November 27, 1926. Serial No. 151,055.

My invention relates to improvements in door closers and has for its object to provide a new and improved door closer having a spring casing provided with a combined stop and hold-back which will limit the opening movement of the door and also hold the door open at the desired point.

Heretofore it has been customary to provide doors with stops independent of the door closer casing which will limit the opening movement of the door at the desired point. In my invention such a stop is embodied in the casing of the closer itself and also acts to hold the door from closing.

15 The following is a description of an embodiment of my invention, reference being had to the accompanying drawings, in which,

Fig. 1 shows a plan view of a door check and closer mounted on a left-hand door, parts being broken away and the door being shown in closed position;

Fig. 2 shows the relation of the parts when the door is open to 90 degrees;

Fig. 3 is an enlarged view, partly in section and partly in side elevation, the section being on the line 3—3, Fig. 2;

Fig. 4 is a detail of an adjustable ring which I use in carrying out my invention; and

Fig. 5 is a detail of a cam which when assembled co-operates with such adjustable ring.

Referring more particularly to the drawings, 2 indicates the frame of a left-hand door 4, which door when it is opened swings in the direction of the arrow. 6 is an ordinary hydraulic door check and closer, with the usual lever 8 connected by the adjustable link 10 to the door frame. 12 is an adjustable ring which by the screw 14 can be clamped in any desired position upon the cap 16 of the check. This cap 16 has a bearing 18 which is surrounded by a cam 20, the bearing being concentric with the usual spring driven shaft 21, to which the lever is connected. The periphery 22 of a flange over-rides the upper portion of the ring 12 so as to cover the space between the cam and the ring 12. The cam 20 is eccentric to the bearing 18 and consequently to the periphery 22 and is connected to the lever arm 8 by a pin 24 which engages the hole 26. This pin 24 passes through a boss 28 on which is mounted the usual spring tension detent 30.

With the construction shown, it will be seen that the cam 20 moves with the arm 8 so as to be partially revolved as the door is opened and closed. The ring 12 is provided with an inward projection 32 which, as 60 the high point 34 of the cam 20 moves toward or away from it, is engaged or disengaged by the cam, the engaging action being a wedging action. With the door closed as in Fig. 1, the cam does not engage the 65 projection 32. When the projection 32 is positioned at the proper point by the adjustment of the ring 12 and the door is swung open 90° to a position shown in Fig. 2, the cam 20 engages the projection 70 32 so that the opening movement of the door is checked, and, furthermore, the wedging action which takes place between the projection 32 and the cam 20 is such that the door is held open against the closing action 75 of the spring of the check. When it is desired to close the door thus held open it is only necessary to use sufficient closing force to withdraw the cam 20 from the projection 32, whereupon the door will close 80 under the normal action of the closing spring.

The pin 24 is held in position by the screw-plug 46 so that the pin 24 can be removed when desired, thus disconnecting the cam 20 85 from the arm 8 when desired. When the pin 24 is removed the cam 20 and stop 32 cease to function for either stop or hold-back purposes.

The invention is applicable to any ordinary style of door closer by simply providing the cap of the door closer with the projection 32 and the cam 20 connected so as to move with the lever arm 8. Except for the cap of the door check and the parts carried thereby, the check shown in the drawings is an ordinary spring closing hydraulic door check, 36 being the usual spring drum casing provided with ears constituting means for directly securing it to the door to be 90 controlled and from which casing the spring driven shaft 21 protrudes and 38 being the usual piston cylinder and 40 being the usual by-pass control. The cap 16 is held from rotation relatively to the spring casing 36 100 in the usual manner by a pin 42 entering a hole in the projection 44 integral with said cap.

By the foregoing simple means a stop and hold-back are embodied in a door closer as 110

integral parts thereof, with very little additional expense, and of efficient durable construction which is not liable to get out of order.

5 If it is desired to adjust the check so that the door shall not be stopped or held back when opened this can be done by simply adjusting the ring 12 so that the cam will not engage the projection 32 in any position 10 of the door, or by removing the pin 24.

By "eccentric" cam I mean a cam whose engaging surface is not concentric with the axis of the actuating shaft, but so shaped that when turned it makes a wedging engagement with the stop 32. The surface of this cam 20 is shown as circular, but while that shape is desirable for manufacturing reasons, the wedging action can be secured with other shaped cams.

20 As will be evident to those skilled in the art, my invention permits of various modifications without departing from the spirit thereof or the scope of the appended claims.

What I claim is:

25 1. In a spring door closer, the combination of a rotatable lever, a cam revolving therewith and having a surface eccentric to the axis thereof, a spring casing and a stationary stop carried by said casing and adapted to be engaged and disengaged by the eccentric surface of said cam during the 30 opening and closing movements of the door, said casing having means for securing it directly to the door to be controlled, and a spring driven shaft protruding from said spring casing, the axis of said cam being concentric with said spring driven shaft.

2. In a spring door closer, the combination of a rotatable lever, a cam revolving therewith and having a surface eccentric to the axis thereof, a spring casing and a stationary stop carried by said casing and adapted to be engaged and disengaged by the eccentric surface of said cam during the 45 opening and closing movements of the door, said stop being angularly adjustable, said casing having means for securing it directly to the door to be controlled, and a spring driven shaft protruding from said spring 50 casing, the axis of said cam being concentric with said spring driven shaft.

3. In a spring door closer, the combination of a rotatable lever, a cam revolving therewith and having a surface eccentric 55 to the axis thereof, and a stationary stop

adapted to be engaged and disengaged by the eccentric surface of said cam during the opening and closing movements of the door, said stop being angularly adjustable, said lever and cam being provided one with a 60 pin and the other with an opening receiving said pin so that said cam revolves with said lever.

4. In a spring door closer, the combination of a rotatable lever, a cam revolving therewith and having a surface eccentric to the axis thereof, a stationary stop adapted to be engaged and disengaged by the eccentric surface of said cam during the opening and closing movements of the door, said 70 stop being angularly adjustable, said cam being provided with an opening, and said lever being provided with a removable pin entering said opening, and a screw-plug holding said pin in position so that said cam and lever move together.

5. In a spring door closer, the combination of a shaft, a lever secured thereto, a spring casing, a cover therefor surrounding said shaft and having an external bearing 80 concentric with said shaft, a cam revolvably externally mounted on said bearing and having a surface eccentric thereto, means connecting said cam and lever, and a fixed stop carried by said casing cover and adapted to be engaged by the eccentric surface of said cam and disengaged thereby as the door opens and closes, said casing having means for securing it directly to the door to be controlled, and a spring driven shaft protruding from said spring casing, the axis of 85 said cam being concentric with said spring driven shaft.

6. In a spring door closer, the combination of a shaft, a lever secured thereto, a 90 spring casing, a cover therefor surrounding said shaft and having an external bearing concentric with said shaft, a cam revolvably externally mounted on said bearing and having a surface eccentric thereto, means connecting said cam and lever, a fixed stop carried by said casing cover and adapted to be engaged by the eccentric surface of said cam and disengaged thereby as the door opens and closes, said cam having a laterally 95 extending flange overlapping said fixed stop.

In testimony whereof, I have signed my name to this specification this 23rd day of November, 1926.

ERNEST L. TEICH.
